UNITED STATES PATENT OFFICE.

JAMES H. BERRY, OF HOUSTON, TEXAS.

DESIGN FOR A BOOMERANG.

SPECIFICATION forming part of Design No. 31,877, dated November 21, 1899.

Application filed October 25, 1899. Serial No. 734,783. Term of patent 7 years.

To all whom it may concern:

Be it known that I, JAMES H. BERRY, a citizen of the United States, residing at Houston, in the county of Harris and State of Texas, 5 have invented and produced a new and original Design for a Boomerang, of which the following is a full, clear, and exact description.

Reference is to be had to the accompanying drawings, in which—

10 Figure 1 is a face view of the boomerang embodying the features of my design, and Fig. 2 is an edge view thereof.

15 The essential feature of my design consists in the design forming the subject of the accompanying drawings.

As shown, the boomerang A has arms B and C, one somewhat longer than the other and

extending approximately at right angles to each other, said arms merging into an elbow D, whose rear edge E is swelled or bulged and 20 whose opposite edge F is regularly curved.

Having thus described my invention, what I claim as new, and desire to secure by Letters Patent, is—

The design for a boomerang herein shown 25 and described.

In testimony whereof I have signed my name to this specification in the presence of two subscribing witnesses.

JAMES H. BERRY.

Witnesses:

JOHN S. PURDY,
NATHAN C. STRONG.
